Application June 23, 1948, Serial No. 34,697

8 Claims. (Cl. 282—1)

1

This invention relates to a register adapted to save time and effort in making records of sales and similar data. It is an object of the invention to provide apparatus to facilitate the posting of items on ledger forms automatically as entries are made on sales slips. According to the invention this is done by providing means for loosely holding together a set of individual ledger cards or forms in such a way that any one of the forms can easily be placed on a supporting surface over one or more sales slips or equivalent forms, each of which is overlaid by carbon paper. Various details of structural improvement are also included in the register which is herein-after described and is illustrated on the drawings, of which—

Figure 1 is a perspective view of a register embodying the invention;

Figure 2 is a sectional view on the line 2—2 of Figure 1;

Figure 3 is a plan view of a sample ledger form;

Figure 4 is a plan view of a portion of a fan-folded strip of printed sales slips;

Figure 5 is a sectional view of the apparatus taken on a longitudinal plane;

Figure 6 is a fragmentary plan view of a portion of the apparatus;

Figure 7 is a section on the line 7—7 of Figure 6;

Figure 8 is a section on the line 8—8 of Figure 6;

Figure 9 is a sectional view similar to Figure 8 but showing the parts in a different position of operation; and

Figure 10 is a section on the line 10—10 of Figure 2.

The invention is shown as embodied in a receptacle which, as illustrated in Figure 1, may be in the form of a trough 20 having a bottom 22 and side walls 24 and 26. These side walls are preferably of considerable thickness and are hollow so as to contain mechanism as herein-after described.

Rising from the bottom 22, near the midpoint thereof, are two arches 28 of a type commonly employed for holding together loosely a stack of papers or forms, in such a manner as to facilitate access to any desired sheet in the stack without disturbing the sequence of the sheets in the stack. Figure 1 shows a stack 30 of printed forms such as that shown in Figure 3. These forms are normally disposed in the forward portion of the trough 20 but any desired number of them can be swung over the arches so as to

lie inverted in the rear portion of the trough, leaving the next successive form on top of the stack. Overlying the stack 30 is a table member 32 which is hinged, as at 34, to the wall 24 and extends across the forward portion of the trough to rest on the wall 26. This table member is of considerable thickness and is hollow, the interior being divided into a number of compartments to hold supplies of forms and carbon paper and being otherwise equipped as herein-after described so that it is in itself a self-contained autographic register.

As shown in Figure 2, a compartment 36 in the table member is adapted to contain carbon paper, one or more strips 38 of carbon paper being made up into a roll adapted to be inserted in the compartment. A lid or cover 40 is provided for the compartment. This may be hinged, as at 42, and spring pressed, as by a spring 44, so as to be maintained resiliently in its closed position. The edge of the cover 40 opposite the hinge 42 does not close tightly but is arranged to leave an opening 46 through which the strip or strips of carbon paper may be drawn from the roll.

The table 32 also has a central compartment 50 adapted to receive and hold a fan-folded strip of blanks or forms 52, such as the sales slip illustrated in Figure 4. The compartment 50 is closed by a lid or top plate 54 which may be conveniently hinged, as at 56, and is spring-pressed toward its closed position. The fan-folded blanks or forms 52 are preferably drawn through a narrow opening 58 (Figure 5) at the rear end of the lid 54 and thence forward across the lid 54 and down through a passage 60 so as to emerge through an opening 62 in the front wall of the table member 32. The fan-folded strip or strips are thus drawn across the table member from rear to front, the carbon paper strip or strips being drawn laterally from left to right across the central portion of the table member.

The free end of the carbon strip or strips 38, which is at the righthand side of the top of the table member 32, is clamped by a suitable clamping device 64 set flush into the top of the table member. The clamping device is best shown in Figure 10 and is mounted on a pair of parallel links 66 within a compartment 68 of the table member 32 so that a push on the projecting end 69 causes the clamp to swing up to a position above the table top. The clamp 64 is provided with a slot 70 through which the carbon paper may be thrust when the clamp is swung up to its elevated position shown in Figure 10. When released, the clamp 64 is pulled down to its flush

position by a spring 72. When the clamp 64 moves down to its flush position, it pinches the carbon paper which has been passed through the slot 70 and thus grips the carbon paper flat against the top of the table member.

The fan-folded strips of forms 52 are provided with suitable perforations 76, two such perforations for each form being shown in Figure 4. Within a transverse compartment 80 of the table member 32 are located two folding and feeding pins 82 which are adapted to enter the holes 76 of a form lying on the table top. The pins 82 thus hold the leading form 52 correctly in a predetermined position on the table top. This is important since it is desirable that when a selected sheet or form from the stack 30 is placed upon the leading form 52 on the table top, the lines and spaces designated on the form 30 accurately overlie and register with the corresponding lines and spaces on the leading form 52, so that entries made in spaces on the topmost form 30 will be duplicated by means of the carbon sheets which are interleaved with the form or forms 52 on the table top.

As is evident from Figure 5, the arches 28 extend above the level of the table top 54 so as to make it possible to select any form from the stack 30 and place it upon the table without disturbing the sequence of the forms in the stack held by the arches. In order to place a selected form 30 on the table top, the forms in the stack which ordinarily overlie it are moved up and over on the arches until they lie inverted in the rear portion of the trough, as indicated in Figure 5, and the selected form is placed on the table top without being detached from the arches. The forms beneath the selected form in the stack remain in their normal position under the table top. This operation is facilitated by swinging the entire table member.

The pins 82 not only hold the form 52 in place on the table top but also serve to feed the strip forward through to project from the slot 62 a sufficient distance to enable the operator to seize the projecting end of the strip and pull it forward until the next successive form in the strip is properly located on the table top. Feeding pins of this description are not new, but in the present apparatus improved actuating means for such pins are provided, as illustrated on the drawings. For the actuation of the pins 82, a transverse horizontal shaft 84 is mounted within the compartment 80 and journaled in partition walls 86 within the compartment 80. The shaft 84 is provided with a suitable operating crank 88 on the end of which a finger button 90 is mounted in a convenient location, such as that illustrated in Figure 1. Secured to the shaft 84 and extending upward therefrom is a plate 92, against a face of which is slidably mounted a second plate 94, this second plate being guided by suitable flanges 96 at the ends of the first plate. The sliding plate is provided with two bent ears 98 at its upper edge to support the pins 82. A pair of springs 100 are stretched between ears 102 at the lower edge of the sliding plate and ears 104 at the upper edge of the plate 92, so as to press the sliding plate and pins 82 yielding upward. The pins 82 project upward through slots 106 in a plate 108 which forms the top of the compartment 80, and normally extend up through slots in a curved plate 110 above the plate 108, these two plates defining the guiding passage 60 through which the strip 52 passes. When the pins 82 pass through the holes 76 of one of the forms in the

5 10 15 20 25 30 35 40 45 50 55 60 65 70 75

strip 52, the projection of the pins through the plate 110 prevents the strip from becoming disengaged until the pins are retracted. For the retraction of the pins 82 at the end of a feeding stroke, a cam is provided. As shown, the cam is a narrow strip portion 112 of the plate 108 which is at the middle of the plate and is curved more sharply downward, as shown in Figures 9 and 10. This cam is engaged by a small wheel or cam follower 114 which is mounted on the sliding plate 94. As is evident from Figures 8 and 9, when the shaft 84 is rocked forward by depression of the finger piece 90, the cam follower 114 rolls on the cam 112 and causes the plate 94 to slide down with the pins 82 as the pins approach the forward end of their feeding stroke. Thus, when the pins have fed the paper strip forward so as to project its end out from the slot 62, the pins are then automatically retracted from the holes 76 in the strip and are beneath the level of the paper strip at that point. In order to maintain the pins 82 in their lowered or retracted position during the return stroke, a latch 116 is pivotally mounted at 118 (Figures 8 and 9), this latch having a trigger 120 which is adapted to engage a lug 122 when the shaft 84 is rocked back to its normal position, and a nose 122 which projects through an opening in the plate 92 and catches on a shoulder 124 in the plate 94 when the latter is moved to its lowered position, as shown in Figure 9. Thus, the depressed plate 94 is held in such position against the pull of the springs 100 until the trigger 120 engages the lug 122, as the shaft 84 completes its rearward swing so as to trip the latch 116 and release the plate 94, thus permitting the springs 100 to elevate the plate 84 and pins 82 upward against the underside of the strip 52. When the strip, which has been projected from the slot 62, is manually pulled outward a sufficient additional distance to bring the top of the leading form in line with the front wall of the table member 32, so that the end form can be torn off, the holes 76 of the next successive form in the strip reach a position of registry over the pins 82, whereupon the pins pass through these holes and through the plate 110, thus locking the form in correct position for use on the table top. At the slot 62 a suitable tearing blade 126 is mounted to facilitate the severing of the leading form from the strip 52.

The table member 32 is hinged to the trough so that it can be swung back to facilitate access to the stack of forms 30 so that a selected form may be placed on the table without being detached from the arches. To prevent injury to the table member, a limiting element 128 may be attached thereto, and a dash-pot 130 may be provided within the hollow wall 26.

We claim:

1. Apparatus of the class described comprising a receptacle with side walls adapted to receive a stack of printed forms, arches on the floor of said receptacle to hold said forms loosely together, a hollow table member carried by said receptacle and spanning the space between said side walls, the tops of said arches rising above the top of said table member so that any of said forms can be laid on the table without being removed from the arches and be maintained by said arches in a predetermined position on the table, and means carried by said table for releasably holding other forms on the top thereof in a predetermined position relative to the arch-positioned form thereon.

2. Apparatus of the class described comprising

a receptacle having side walls, means in said receptacle adapted to hold loosely therein a stack of forms assembled in a predetermined order, a hollow table member hinged to one side wall and normally extending to the other side wall said table member having a chamber for a supply of fan folded forms, dash-pot means in said other side wall to check said table member when rocked to its normal position, and means for limiting the extent of rocking movement of the table away from its normal position.

3. Apparatus of the class described comprising an open ended trough adapted to receive a stack of printed forms, a table normally spanning said trough and movable from said position to provide ready access to the trough, arches mounted in said trough adjacent to an end of said table to hold said printed forms loosely assembled and to position correctly any one of said forms upon said table, and means carried by said table for holding other forms in a predetermined position thereon.

4. Apparatus of the class described comprising a trough with vertical side walls, a complete autographic register spanning said trough and hinged to one wall thereof, said register including a top plate, and means for holding strip forms in correct position in the top plate, and arches in said trough adjacent to one end of said register for holding a stack of forms loosely assembled in the trough beneath said register and for locating any selected form from said stack upon and in registry with the forms held on said top plate.

5. Apparatus of the class described comprising a trough having hollow vertical walls, a self-contained register spanning said trough and hinged to one wall thereof whereby the register can be swung back to open the trough, a dashpot device mounted within the other of said walls and engageable by said register when the register is rocked to its trough-spanning position, arches within said trough adjacent to one end of said register to hold a stack of forms loosely assembled within the trough and to position any selected one of said forms upon the top of the register.

6. Apparatus of the class described comprising a trough having side walls of substantial height to accommodate a large number of record cards stacked therein, an autographic register sup-

ported on the tops of said walls and including means for releasably holding record blanks in a predetermined position on the register, and means carried by the trough for holding said record cards loosely assembled and for aligning any selected card with said record blanks when laid thereon.

7. Apparatus of the class described comprising a base, a self-contained register mounted above said base and vertically spaced therefrom, and means on said base for holding a series of separate leaves in a definite sequence and guiding any selected leaf from a position under said register to a predetermined position on top of said register, said register comprising a hollow box having a compartment for a supply of multiple strips of printed forms, means for temporarily holding the leading forms in position on the top of the box to be overlain by any selected one of said leaves in said predetermined position.

8. Apparatus of the class described comprising a base, a self-contained register carried by said base and spaced thereabove, said register comprising a hollow box having a flat top, a compartment for a supply of multiple strips of printed forms and means for locating successive forms accurately in a predetermined position on said top, and means on said base for maintaining a series of record leaves in a definite order below said box and for guiding any selected leaf into a superposed position on the forms on said top in registry therewith.
